UNITED STATES PATENT OFFICE

148,525

DESIGN FOR A COMBINATION CONFEC- TIONERS' AND BAKERS' MIXER AND COOKER

Rubin M. Dubin, Los Angeles, Calif.

Application August 19, 1946, Serial No. 132,662

Term of patent 14 years

(Cl. D44—1)

To all whom it may concern:

Be it known that I, Rubin M. Dubin, a citizen of the United States and resident of the city of Los Angeles, county of Los Angeles, and State of California, have invented a new, original, and ornamental Design for Combination Confectioners' and Bakers' Mixer and Cooker, of which the following is a specification, reference being had to the accompanying drawings, forming part thereof, in which:

Fig. 1 is a front perspective view of a combination confectioners' and bakers' mixer and cooker in operative position showing my new design;

Fig. 2 is a side elevational view showing the mixer in operative position;

Fig. 3 is a front perspective view showing the mixer in inoperative position and with the mixing

bowl omitted for convenience of illustration; and Fig. 4 is a rear elevational view showing the mixer in inoperative position.

I claim:

The ornamental design for a combination confectioners' and bakers' mixer and cooker, as shown.

RUBIN M. DUBIN.
